Attorney.

UNITED STATES PATENT OFFICE

2,507,165

COLLAPSIBLE CONVERTIBLE ROCKING
CHAIR

Casper Kreutzer, Milltown, N. J.

Application April 28, 1949, Serial No. 90,123

7 Claims. (Cl. 155—73)

1

This invention relates to improvements in chairs of the type which are convertible for optional use either as a stationary or standing chair or as a rocking chair.

Chairs adapted to be converted for either standing or rocking use are known to the art, and usually include rocker members which are pivotally connected with the chair structure so as to be capable of being moved to and from out of service position from and to service position. Chairs of such type have not appeared to have met with much popular favor for the reason, it is believed, that the structures thereof have either been too complicated and difficult to operate in effecting conversion, or, when converted to rocking condition, did not adequately secure the rocker members in service position and assure stability in such position.

Having these circumstances in view, it is the purpose of this invention to provide a convertible chair wherein rocker members are respectively pivotally connected to the respective front legs of the chair, so as to extend between said front legs and the rear legs of the chair, and so as to swing about their pivotal connections to and from out of service position from and to service position; novel and easily manipulatable means of simple structure being provided in connection with the rear legs of the chair adapted to releasably engage the rocker members so as to firmly and securely unite the same with the rear chair legs so as to provide the chair with rocking support; said latter means being so constructed and arranged as not to appreciably alter the conventional appearance of the chair, and also being of such character and disposition as to avoid externally projecting parts which might likely be accidentally and detrimentally engaged by the person or the clothing of the users.

Illustrative embodiments of the invention are shown in the accompanying drawings, in which:

Fig. 1 is a perspective view of a convertible chair according to this invention as conditioned for stationary or standing use; and Fig. 2 is a similar perspective view of the chair as conditioned for rocking use.

Fig. 3 is a transverse sectional view, taken on line 3—3 in Fig. 2, but drawn on an enlarged scale.

Fig. 4 is a fragmentary sectional view similar to that of Fig. 3, but showing a modified arrangement of the means for securing a rocker member in service position to convert the chair for rocking use.

Fig. 5 and Fig. 6 are fragmentary sectional

views showing modified forms of means for pivoting a rocker member to a front chair leg.

Similar characters of reference are employed in the hereinabove described views, to indicate corresponding parts.

The rocker members for the convertible chair, including the means for releasably holding the same in either service or out of service relation to the chair structure, can be applied to either a folding chair having relatively foldable front and rear leg frames and back rest, or to a chair of rigid structure or non-folding type having immovable front and rear legs.

For the purposes of illustration, however, the rocker members are shown in the drawings as operatively applied to a folding type of chair comprising crossed pivotally connected front and rear seat supporting leg frames 10 and 11 and a pivotally connected back rest 12.

Pivotally connected by their forward ends respectively with the foot portions 13 of the front leg frame 10 are rocker members 14. Such pivotal connection can be provided by a solid rung 15 which is mounted in and between said foot portions 13, so that the end portions of said rung project through the forward end portions of the rocker members 14; said rung end portions being screw-threaded to receive thumb nuts 16, or like means, for holding the rocker members operatively assembled with and in pivotal relation to said foot portions 13 of the front leg frame 10 (see Figs. 1 and 2).

Alternative means for pivotally mounting the rocker members 14 in assembled pivoted relation to the foot portions 13 of the front leg frame 10 are shown in Figs. 5 and 6. In one such arrangement, as shown in Fig. 5, a tubular rung 17 is connected with and so as to extend between the foot portions 13 of the front leg frame 10. The outwardly open end portions of the tubular rung 17 are provided with internal screw-threads 18. Extending through the forward end portion of each rocker member 14 is a pivoting bolt, the screw-threaded shank 19 of which screws into the adjacent internally screw-threaded end 18 of the rung 17. Said bolt is provided at its outer end with an elongated head 20, which is adapted to be disposed either laterally or longitudinally relative to the length of the rocker member 14 as to lap a substantial area of the outer surface of the latter which is adjacent to the pivotal connection established by the bolt, whereby to stabilize the rocker member against undue lateral play or lateral wobbling or swinging movement.

A similar but somewhat modified arrangement is

shown in Fig. 6, wherein, in place of the tubular rung 17 that extends through a foot portion 13 of the front leg frame, a socket piece 21 having an outwardly open internally screw-threaded bore 22 is provided; said socket piece having integral or unitary therewith a laterally extending bracket or supporting plate 23 which is adapted to be applied to the rear surface of a leg frame foot portion 13, and to be secured to the latter by fastening rivets or screws 24, or other suitable attaching means. The socket piece 21 is thus applied to the leg frame foot portion 13 with its open end outwardly presented, whereupon a threaded shank 19 of a pivoting bolt, of the kind above described, is passed through the forward end portion of a rocker member 14, so that the elongated head 20 thereof engages and laps the outer face of the latter, in the same manner and for the same purpose as already above set forth.

The rocker members 14, being pivotally connected to the foot end portions 13 of the front leg frame 10, as above explained, the same are capable of being up swung to out of service positions when the chair is to be conditioned for stationary standing or non-rocking use, as shown in Fig. 1. Means is provided for releasably retaining the rocker members 14 in such swung out of service positions. An illustrative form of such means, as shown, comprises spring clips 25 which are affixed to and which project rearwardly from the upper end portions of the front leg frame 10, or from other suitable parts of the rearward portion of a chair structure. Said spring clips 25, in the illustrative form thereof as shown, comprise flexibly resilient metallic plates or leaf spring bodies, which terminate at their free ends in retainer lips 26 angularly disposed for inward projection therefrom. It will be obvious that, when the rocker members 14 are up swung to out of service position, the clips 25 may be outwardly flexed to permit the free end portions of said rocker members to move upwardly past the retainer lips 26 until abutted against the adjacent portions of the leg frame, whereupon the flexed clips are leased for inward movement of their retainer lips 26 into embracing and holding relation to the rocker members (see Fig. 1).

When it is desired to condition the chair for rocking use, the rocker members 14 are released from above described up swung retained condition, and are thereupon down swung to dispose their rearward end portions adjacent to the foot portions 27 of the rear leg frame 11 of the chair. Novel means is provided for releasably coupling or interlocking the down swung rocker members with said rear leg frame foot portions 27, whereby to affix said rocker members to the latter in service position. In a preferred form of such means, a tubular rung 28 is connected with and so as to extend between the foot portions 27. Slidably mounted in each outwardly open end portion of the tubular rung 28 is a locking bolt 29. Contained within the tubular rung 28 is compression spring means 30. Said spring means 30 is adapted to engage the inner ends of the locking bolts 29 so as to tensionally exercise thereupon yieldable outwardly projecting thrust.

Provided in the respective wall portions of the tubular rung 28 which house the respective locking bolts 29 are slotways 31. These slotways are provided at their inner ends with inner bayonet slots 32 extending laterally therefrom, and with similar bayonet slots 33 at their outer ends. The bolts 29 are each provided with laterally extending finger pieces 34 which project through and

are adapted to ride in the adjacent slotways 31.

When the rocker members 14 occupy retained up swung out of service positions, the bolts 29 are disposed in retracted positions against the thrust of the spring members 30, so as to be withdrawn into the tubular rung 28, the bolts being retained in such withdrawn positions by swinging the finger pieces 34 thereof into the inner bayonet slots 32 of the slotways 31. The locking bolts being thus withdrawn, and retained withdrawn, free the outer sides of the foot portions 27 from undesirable projection of the bolt ends, so that not only are the rocker members unimpeded when down swung to service relation to the rear foot portions 27, but also outward projections from said foot portions are eliminated, so as to avoid risk of injury to foot wear or to the persons of those moving about the chair.

To operatively interlock the down swung rocker members 14 with the rear foot portions 27, when converting the chair for rocking use, the rearward end portions of said rocker members are provided with locking bolt receiving openings or sockets 35, which are adapted to be aligned with the axes of the locking bolts when the rocker members are lowered to service positions. Upon alignment of said openings or sockets 35 with the locking bolts 29, the latter are released from retracted positions by swinging their finger pieces 34 out of the inner bayonet slots 32 into the slotways 31. The locking bolts 29, when thus released, will be outwardly moved by spring means 30, whereby to project their outer end portions into the aligned openings or sockets 35, thus interlocking the rocker members in operative fixed relation to the rear foot portions 27 of the chair frame. The locking bolt, when thus engaged with the rocker members, can be secured against accidental release from the latter by swinging the finger pieces 34 thereof into the outer bayonet slots 33 (see Fig. 3).

In chair constructions wherein a complete rung extending between the foot portions of the rear leg structure is undesirable, a modified mounting of the locking bolts of the kind shown in Fig. 4 may be used. Such modified arrangement comprises a socket piece 36 for each rear leg foot portion having an outwardly open bore 37. Integral or unitary with said socket piece 36 is a laterally extending bracket or supporting plate 38 which is adapted to be applied to the rear surface of a rear leg foot portion 27, and to be secured thereto by fastening rivets or screws 39, or other suitable attaching means. Slidably mounted in the bore 37 of the socket piece 36 is the locking bolt 29, behind which is arranged spring means 30, whereby to project the locking bolt from the outer open end of the socket piece 36. Provided in the wall of the socket piece 36 is a slotway 31 which is formed at its inner end to provide an inner bayonet slot 32 and at its outer end to provide an outer bayonet slot 33. It will be obvious that manipulation and use of the locking bolt in this modified mounting thereof is the same as above described with respect to the rung mounting of said locking bolts.

Although application of the convertible rocker structure according to this invention has been above described with respect to its application to chair construction, it will be obvious that it can also be applied to other articles of furniture which is desired to be provided for conversion to and from stationary or standing condition from and to a rocking condition, such, for ex-

ample, as a child's crib adapted for either stationary use or for rocking use in the manner of a cradle.

Having now described my invention, I claim:

1. In a chair or other article of furniture convertible for stationary or rocking use and having front and rear legs, rocker members adapted to be optionally positioned in service or out of service condition, means to pivotally connect forward end portions of the rocker members to the foot portions of the front legs, means to releasably hold the rocker members in up swung out of service condition, means to releasably hold the rocker members in down swung service condition, said latter means comprising locking bolts, housing means for slidably supporting the locking bolts affixed to the foot portions of the rear legs, said rocker members having locking bolt receiving apertures into which the locking bolts can be projected, spring means for projecting the locking bolts, said locking bolts having laterally extending finger pieces, said housing means having longitudinal slotways through which said finger pieces extend, and said slotways terminating at their respective inner and outer ends in bayonet slots into which the finger pieces may be turned, whereby to releasably retain said locking bolts in retracted or projected positions as the case may be.

2. In a chair or other article of furniture convertible for stationary or rocking use and having front and rear legs, rocker members adapted to be optionally positioned in service or out of service condition, means to pivotally connect forward end portions of the rocker members to foot portions of the front legs, means to releasably hold the rocker members in up swung and out of service condition, means to releasably hold the rocker members in down swung service condition, said latter means comprising a tubular rung connected with and extending between the foot portions of the rear legs, locking bolts respectively slidably mounted in respective outer end portions of the rung, means for manipulating said locking bolts, and said rocker members having locking bolt receiving apertures into which the locking bolts can be projected.

3. In a chair or other article of furniture convertible for stationary or rocking use and having front and rear legs, rocker members adapted to be optionally positioned in service or out of service condition, means to pivotally connect forward end portions of the rocker members to foot portions of the front legs, means to releasably hold the rocker members in up swung out of service condition, means to releasably hold the rocker members in down swung service condition, said latter means comprising a tubular rung connected with and extending between the foot portions of the rear legs, locking bolts respectively slidably mounted in respective outer end portions of the rung, spring means within the rung for projecting the locking bolts, said locking bolts having laterally extending finger pieces, said rung having longitudinal slotways through which said finger pieces extend, said slotways terminating at their respective inner and outer ends in bayonet slots into which the finger pieces may be turned, whereby to releasably retain said locking bolts in retracted or projected positions as the case may be, and said rocker members having locking bolt receiving apertures into which the locking bolts can be projected.

4. A folding chair convertible for stationary or rocking use comprising pivotally connected front

and rear seat supporting leg frames and a foldable back rest, rocker members adapted to be optionally positioned in service or out of service condition, means to pivotally connect forward end portions of the rocker members to foot portions of the front leg frame, spring clips mounted on the upper portions of the front leg frame adapted to releasably engage and hold the rocker members in up swung out of service condition, means to releasably interlock the rocker members to the foot portions of the rear leg frame when said rocker members are down swung to service condition, said latter means comprising locking bolts, housing means for slidably supporting the locking bolts affixed to the foot portions of the rear leg frame, and said rocker members having lock bolt receiving apertures into which the locking bolts can be projected.

5. A folding chair convertible for stationary or rocking use comprising pivotally connected front and rear seat supporting leg frames and a foldable back rest, rocker members adapted to be optionally positioned in service or out of service condition, means to pivotally connect forward end portions of the rocker members to foot portions of the front leg frame, spring clips mounted on the upper portions of the front leg frame adapted to releasably engage and hold the rocker members in up swung out of service condition, means to releasably interlock the rocker members to the foot portions of the rear leg frame when said rocker members are down swung to service condition, said latter means comprising locking bolts, housing means for slidably supporting the locking bolts affixed to the foot portions of the rear leg frame, and said rocker members having lock bolt receiving apertures into which the locking bolts can be projected, spring means for projecting the locking bolts, said locking bolts having laterally extending finger pieces, said housing means having longitudinal slotways through which said finger pieces extend, and said slotways terminating at their respective inner and outer ends in bayonet slots into which the finger pieces may be turned, whereby to releasably retain said locking bolts in retracted or projected positions as the case may be.

6. A folding chair convertible for stationary or rocking use comprising pivotally connected front and rear seat supporting leg frames and a foldable back rest, rocker members adapted to be optionally positioned in service or out of service condition, means to pivotally connect forward end portions of the rocker members to foot portions of the front leg frame, spring clips mounted on the upper portions of the front leg frame adapted to releasably engage and hold the rocker members in up swung out of service condition, means to releasably interlock the rocker members to the foot portions of the rear leg frame when said rocker members are down swung to service condition, said latter means comprising a tubular rung connected with and extending between the foot portions of the rear leg frame, locking bolts respectively slidably mounted in respective outer end portions of the rung, means for manipulating said locking bolts, and said rocker members having locking bolt receiving apertures into which the locking bolts can be projected.

7. A folding chair convertible for stationary or rocking use comprising pivotally connected front and rear seat supporting leg frames and a foldable back rest, rocker members adapted to be optionally positioned in service or out of service condition, means to pivotally connect forward end por-

tions of the rocker members to foot portions of the front leg frame, spring clips mounted on the upper portions of the front leg frame adapted to releasably engage and hold the rocker members in up swung out of service condition, means to releasably interlock the rocker members to the foot portions of the rear leg frame when said rocker members are down swung to service condition, said latter means comprising a tubular rung connected with and extending between the foot portions of the rear leg frame, locking bolts respectively slidably mounted in respective outer end portions of the rung, spring means within the rung for projecting the locking bolts, said locking bolts having laterally extending finger pieces, said rung having longitudinal slotways through which said finger pieces extend, said slotways terminating at their respective inner and outer ends in bayonet slots into which the finger pieces may be turned, whereby to releaseably retain said locking

10
